CARRIER-WAVE COMMUNICATION SYSTEM

Harold M. Lewis, Allenhurst, N. J., assignor, by
mesne assignments, to Hazeltine Research, Inc.,
Chicago, Ill., a corporation of Illinois

Application October 8, 1941, Serial No. 414,050

19 Claims. (Cl. 250—6)

1

The present invention relates to carrier-wave communication systems and, particularly, to systems of this nature which employ mobile transmitter apparatus of relatively low power for communication over relatively short distances.

It is frequently desirable that communication over distances of a mile or so be effected by a carrier-wave communication system which utilizes a transmitter apparatus of relatively low power. An example of this nature occurs in military operations where it is essential that a forward military unit be able to transmit information to a rear position. Although the distances to be covered may be only of the order of a mile or less, it has heretofore been necessary that the transmitting apparatus carried by the forward unit be provided with some form of power supply, generally one or more storage batteries or dry batteries or perhaps a hand-driven generator, by which to energize the transmitting apparatus. The reduction of weight of any apparatus carried by the forward unit is of paramount importance not only from the standpoint of maintaining a high degree of mobility of the apparatus but also to minimize the number of persons required to transport it. Dry batteries have a limited life and replacements must be carried by the forward unit or a line of supply be maintained to that unit. This applies with even greater force to the use of storage batteries which require periodic and frequent recharging. This problem is particularly troublesome in connection with a conventional transmitting apparatus which places a relatively heavy drain on the power source from which it is energized. To maintain an uninterrupted line of supply to a forward unit engaged in combat is in many cases exceedingly difficult and frequently impossible. Consequently, communication with such forward units may be subject to frequent and undesired interruptions due to the supply problem itself where energization of the transmitting equipment is by batteries. Energization by hand-driven generators has the important disadvantage that at least two men are required to transport and operate each generator unit.

It is an object of the present invention, therefore, to provide a new and improved carrier-wave communication system of the type described which avoids one or more of the disadvantages and limitations of the prior systems of this nature.

It is an additional object of the invention to provide a carrier-wave communication system having one or more transmitter units which re-

2

quire no local source of energizing power and which, therefore, may be compact, of light weight, and of inexpensive construction insuring a high degree of mobility and reliability of operation.

3 It is a further object of the invention to provide a carrier-wave communication system having a transmitter apparatus adapted to be effectively energized solely by radiant energy from other transmitting apparatus located at a remote point 10 therefrom, yet one which is of simple and rugged construction.

In accordance with the invention, a carrier-wave communication system comprises a transmitting station including means for generating 15 and directly radiating a modulated carrier wave as well as carrier-wave radiating means remotely situated from the station and adapted to be energized solely by the aforementioned carrier wave and thereby to reradiate carrier-wave energy directly radiated thereto from the station. The system includes means for modulating the reradiated carrier wave with the desired signal to be transmitted, means for receiving the reradiated carrier wave and dependent upon the modulation 25 of the radiated carrier wave for deriving from the received carrier wave the desired modulation-signal components thereof, and means coupled to the last-mentioned means for utilizing the desired modulation-signal components.

30 In one form of the invention, a carrier-wave communication system of the type described comprises a transmitting station including means for generating and directly radiating a carrier wave frequency-modulated with a periodic modulating 35 signal of approximately saw-tooth wave form. The system includes an antenna means remotely situated from the station and tuned to the nominal frequency of the carrier wave to re-radiate the carrier-wave energy directly radiated thereto from the station. The system also includes means for modifying the tuning of the antenna means to modulate the re-radiated carrier wave with the desired signal to be transmitted.

40 45 In a particular form of the invention, the antenna means may comprise a loop antenna and the means for modifying the tuning of the antenna may comprise circuit-interrupting means included in circuit with a winding of the loop antenna.

For a better understanding of the present invention, together with other and further objects thereof, reference is had to the following description taken in connection with the accompanying

drawings, and its scope will be pointed out in the appended claims.

Referring now to the drawings, Fig. 1 represents a circuit diagram, partly schematic, of a complete carrier-wave communication system embodying the present invention; Figs. 2 and 3 are graphs illustrating certain operating relations occurring in the arrangement of Fig. 1 and are used as an aid in explaining the operation of the invention; Fig. 4 is a circuit diagram, partly schematic, of a portion of a complete carrier-wave communication system and represents a modified form of the invention; Fig. 5 is a graph representing a certain operating condition occurring in the arrangement of Fig. 4 and is used as an aid in explaining the operation thereof; and Fig. 6 represents a modified form of the Fig. 4 arrangement.

Referring now more particularly to Fig. 1 of the drawings, there is represented schematically a complete carrier-wave communication system embodying the present invention in a preferred form. The system includes a transmitting station 10 including means for generating and directly radiating a carrier wave frequency-modulated with a periodic modulating signal of approximately saw-tooth wave form. This means comprises an amplifier 11 having an output circuit coupled to a dipole antenna 12, 13 and having an input circuit coupled to the output circuit of a frequency-modulated oscillator 14. The oscillations generated by the oscillator 14 are frequency-modulated with a periodic modulating signal applied to the oscillator 14 from a modulation-signal generator 15. The latter generates a modulating signal of approximately symmetrical or linear saw-tooth wave form and may comprise, for example, a condenser rotated at constant speed by a motor 16 which is energized from an alternating-current source 17. Means is provided for amplitude-modulating the carrier wave generated by the frequency-modulated oscillator 14 comprising a manually-operable key 18 which is coupled to a modulation circuit of amplifier 11 in conventional manner.

The carrier-wave communication system also includes carrier-wave radiating means remotely situated with respect to the transmitting station 10 and adapted to respond to a carrier wave radiated by the transmitting station and to re-radiate carrier-wave energy directly radiated to the remotely-situated carrier-wave radiating means from the transmitting station 10. This means comprises a loop antenna 19 and means for tuning the antenna 19 to the nominal frequency of the carrier wave radiated by the transmitting station 10 comprising a condenser 20 connected in circuit with the loop antenna. There is also included means for modifying the tuning of the antenna 19 to modulate the carrier wave re-radiated thereby with the desired signal to be transmitted comprising circuit-interrupting means, here represented as a manually-operable key 21, included in circuit with the winding of the loop antenna 19.

The system also includes means situated at a point remote from the antenna 19 for receiving the re-radiated carrier wave and dependent upon the modulation of the radiated carrier wave for deriving from the received carrier wave the desired modulation-signal components thereof. This means comprises a carrier wave receiver 22 which is here shown as being positioned in the general locality of the transmitting station 10. The receiver 22 includes a detector 23 having an

input circuit coupled to a dipole antenna 24, 25 and having an output circuit coupled to the input circuit of an audio-frequency amplifier 26, which may include one or more stages of amplification, having an audio-frequency band-pass filter 27 included in the signal channel thereof. The output circuit of the amplifier 26 is coupled to a signal-reproducing device, for example, a pair of headphones 28 for utilizing the desired modulation-signal components.

Considering now the operation of the carrier-wave communication system just described, and referring to the curves of Fig. 2, the carrier wave generated by the transmitting station 10 and directly radiated from the antenna 12, 13 is frequency-modulated by the saw-tooth modulation signal generated by unit 15 and thus varies between a lower frequency f_1 and an upper frequency f_2 as represented by curve A. This carrier wave travels to the antenna 19 and, assuming that the key 21 is operated to close its contacts, is re-radiated by antenna 19. That is, the electromagnetic component of the radiated wave from the transmitting antenna 12, 13 cuts the loop antenna 19 and induces a current therein which sets up an opposing electromagnetic field 180 electrical degrees out of phase with the electromagnetic field of the directly-radiated carrier wave at the loop antenna 19. This opposing electromagnetic field constitutes the re-radiated carrier wave of the antenna 19. In this connection, it may be noted that the re-radiated carrier wave of antenna 19 is commonly referred to as a reflected carrier wave, but actually there is no essential difference since the latter merely is the observed result of the fact that an opposing electromagnetic field is set up in the antenna 19. Thus, the re-radiated carrier wave of the antenna 19 is of the same character as a reflected carrier wave from any conductive object positioned in the path of the directly-radiated carrier wave. Since the strength of the opposing electromagnetic field set up by the antenna 19 varies with the current flowing therein, it will be seen that the tuning of the antenna 19 to the nominal frequency of the directly-radiated carrier wave results in the maximum flow of carrier-wave current therein and thus the maximum opposing electromagnetic field being set up by the loop antenna 19, or, in other words, insures that the re-radiated carrier wave shall have maximum intensity. The re-radiated carrier wave thus has the same intensity as does the directly-radiated carrier wave at the loop antenna 19, except for the circuit losses of the latter due to its inherent resistance. The circuit losses, of course, are supplied by absorption from the directly-radiated carrier wave. Hence, for maximum intensity of the radiated carrier wave, the resistance of the antenna 19 should be minimized. The re-radiated carrier wave is received by the dipole antenna 24, 25 after a lapse of time t_1 which is required for the directly-radiated carrier wave to travel from the transmitting station 10 over the distance r to the antenna 19 and for the re-radiated carrier wave to travel from the antenna 19 over the same distance to the antenna 24, 25. The re-radiated carrier wave received by the antenna 24, 25 thus varies in frequency as represented by curve B, and is applied to the input circuit of the detector 23. The antenna 24, 25 is relatively closer spaced to the transmitting antenna 12, 13 and thus receives the directly-radiated carrier wave, represented by curve A, and applies this carrier wave also to the input circuit of the

detector 23. There is thus applied to the input circuit of the detector 23 two carrier waves which vary in relative frequency. Since the directly-radiated and reradiated carrier waves are exactly out of phase at the antenna 19, there will be developed in the space between the antennas 12, 13 and 19 standing carrier waves varying in intensity from zero at one point in space to the sum of the directly-radiated and reradiated carrier waves at another point in space. The nominal frequency of the directly-radiated carrier wave should be so chosen in relation to the distance r that the standing carrier wave will have a substantial intensity at the receiving antenna 24, 25. From these applied carrier waves, the detector 23 derives in its output circuit a beat-frequency signal, represented by curve C, which has a constant value of frequency f_3 during the time intervals t_2, t_2' , etc., the constant frequency f_3 of this signal being within the audio-frequency range and varying with the distance r of the loop antenna 19 from the transmitting station 10. This beat-frequency signal is applied to the audio-frequency amplifier 26 where it is amplified and applied to the telephones 28 for reproduction thereby.

Assume now that at a time t_3 the key 21 is operated to open its contacts. The antenna 19 is now no longer responsive to the carrier wave radiated thereto from the transmitting station 10, since the loop winding of antenna 19 is now tuned by its inherent capacitances to some frequency remote from that of the directly-radiated carrier wave, and hence does not reradiate any carrier wave. Consequently, no beat-frequency signal is developed in the output circuit of the detector 23 and no sound is produced in the telephones 28 until the key 21 is again closed, as at the time t_4 to render the antenna 19 again responsive to the carrier wave directly radiated thereto. It will thus be evident that the key 21 is effective to amplitude-modulate the carrier wave reradiated by the antenna 19 with the desired signal to be transmitted, which signal, in the arrangement of Fig. 1, will be a coded signal of dots and dashes of conventional form. In this connection, it will be understood that for purposes of simplifying the description of the operation of the invention, the keying time interval t_3-t_4 in Fig. 2 is not drawn to scale with respect to the period t_1-t_2 of the modulation signal generated by unit 15 and in practice the latter will be much shorter than any keying interval.

Accidental reflections of the carrier wave radiated by the transmitting station 10 may occur from surrounding objects, as houses and trees, and will be received by the antenna 24, 25 to produce in the output circuit of the detector 23 corresponding beat-frequency signals, but these will be of constant tone, of different pitch, and of less amplitude than those produced by the desired signals. It will, therefore, be easy to distinguish the louder keyed signal from the spurious undesired signals produced by such accidental reflections of the directly-radiated carrier wave. However, further to guard against interference from such accidental reflections, the amplifier 26 includes the audio-frequency band-pass filter 27 which may be sharply tuned to the constant frequency f_3 of the beat-frequency signal produced by re-radiation from the antenna 19, thus rejecting all spurious beat-frequency signals which do not have a frequency approximately that of the desired signal.

The nominal frequency of the carrier wave

radiated by the transmitting station 10 preferably lies in the high-frequency portion of the frequency spectrum. This not only reduces the physical size of the loop antenna 19 for optimum response to the radiated carrier wave, but additionally permits the use of directive radiators in place of the dipole antenna 12, 13 or in conjunction therewith, thereby to increase the intensity of the carrier wave at the antenna 19.

The antenna 24, 25 is preferably so arranged that it does not receive an undue excitation from the directly-radiated carrier wave. This may be accomplished by arranging the antennas 12, 13 and 24, 25 in physical proximity with the dipole elements radiating from the same central point and by arranging the antenna 24, 25 at right angles to the antenna 12, 13.

Instead of developing a beat-frequency signal in the output of the detector 23 it will be evident that any conventional form of detector may be used for detector 23 by which directly to detect the amplitude-modulation components of only the carrier wave reradiated by the loop antenna 19. In this event, the antenna 24, 25 should be well shielded from the antenna 12, 13 and the directly-radiated carrier wave and the reradiated carrier wave may have the same constant frequency, if desired.

It can be shown that the constant frequency f_3 of the beat-frequency signal developed in the output circuit of the detector 23 from the directly-radiated and reradiated carrier waves has a value determined from the following relation:

$$F_d = \frac{(F_{dv} T_m \pm \sqrt{F_{dv}^2 T_m^2 - 4 T_m F_{dv} M})}{2 T_m} \quad (1)$$

where:

F_d =the value of the constant frequency f_3 of the developed beat-frequency signal.

F_{dv} =the range of frequency deviation of the directly-radiated carrier wave,

T_m =one-half the period of the modulation signal generated by unit 15,

M =the number of cycles of F_d in the interval t_2

A representative variation of the beat-frequency signal f_3 with the distance r of the loop antenna 19 from the transmitting station 10 is represented by curve D of Fig. 3. It will be evident from this curve that the beat-frequency signal has a minimum useful value at a short distance r_1 and a maximum useful value at a longer distance r_2 , which limitations are placed upon the apparatus by the range of beat-frequency signals which are audible. The minimum useful range r_1 may be decreased by decreasing the period T_m of the modulation signal generated by unit 15 or by increasing the range of frequency deviation F_{dv} of the directly-radiated carrier wave. Correspondingly, the maximum useful range r_2 of the system may be increased by increasing the period of the modulation signal or by decreasing the range of frequency deviation of the directly-radiated carrier wave.

The loop antenna 19 normally will have sufficient inherent resistance to be responsive to the directly-radiated carrier waves over the entire range of frequency deviation of the latter. If this is found not to be the case, a resistor of small value may be inserted in circuit with the loop antenna 19, thereby broadening its response. Any resistance in antenna 19 decreases the intensity of the reradiated carrier wave, as previously pointed out. It is preferable, therefore, to maintain the resistance of the antenna as low as pos-

sible consistent with adequate response of the antenna to the directly-radiated carrier wave over the range of frequency deviation of the latter. In practice, the inherent resistance of the loop antenna 19, even though kept at a minimum value, will generally be more than adequate for this purpose since the range of frequency deviation of the directly-radiated carrier wave will be small in comparison with the nominal frequency thereof, especially where the nominal frequency is quite high, for example, above 20 or 30 megacycles.

From the above description of the Fig. 1 arrangement, it will be evident that the key 21 comprises means coupled to the carrier-wave re-radiating means comprising the antenna 19 for effectively modifying the response thereof to the directly-radiated carrier wave to modulate the reradiated carrier wave with the desired signal to be transmitted. In other words, the key 21 effectively modifies the tuning of the antenna 19 to the directly-radiated carrier wave, thereby to modulate the reradiated carrier wave with the desired signal to be transmitted.

Fig. 4 represents schematically a portion of a carrier-wave communication system and shows a modified form of the carrier-wave radiating means which is remotely situated from the transmitting station. In this modified form of the invention, the carrier-wave radiating means comprises an antenna system shown as a dipole antenna 29, 30. Since it may be desirable to mount the dipole antenna upon a mast, a resonant transmission line 31 is coupled to the antenna to permit this to be done. The resonant transmission line, which may be either a real or artificial line in the form of an impedance network or a combination of the two, has an effective electrical length of one-half or multiples of one-half of the nominal wave length of the carrier wave radiated by the transmitting station. Circuit-interrupting means, comprising a manually-operable key 32, is coupled to the transmission line 31 selectively to short-circuit and open-circuit the remote end thereof and thereby modify the resonant characteristic of the line. This causes the antenna respectively to reradiate and not to reradiate the directly radiated carrier-wave energy, thereby to modulate the reradiated carrier wave with a desired signal to be transmitted. This modified form of the invention also includes means coupled to the carrier-wave radiating means for deriving from the directly-radiated carrier wave a desired modulation signal with which the latter carrier wave has been modulated, as by operation of the key 18 of the Fig. 1 arrangement. This means comprises a carrier-wave receiver 33 having an input circuit coupled through a transmission line 34 to a quarter wave length or potential antinode point of the transmission line 31. The transmission line 34 is terminated by a resistor 35 to avoid reflections. The receiver 33 includes an oscillator-modulator 36 which is coupled to the transmission line 34 for converting a received carrier wave to an intermediate-frequency carrier wave. Coupled to the output circuit of the oscillator-modulator 36, in the order named, are an intermediate-frequency amplifier 37 of one or more stages, a frequency detector 38, an audio-frequency amplifier 39 of one or more stages, and a signal-reproducing device comprising a pair of headphones 40. The detector 38 comprises an input transformer 41 having primary and secondary windings tuned to the nominal frequency of the carrier wave applied thereto from the intermediate-fre-

quency amplifier 37. The detector also includes a rectifier device 42 and load impedance 43 therefore, the load impedance being coupled to the input circuit of the audio-frequency amplifier 39.

5 The operation of this modified form of the invention is essentially similar to that of the Fig. 1 arrangement insofar as the reradiation of a received carrier wave is concerned. That is, the antenna 29, 30 sets up an electromagnetic field 10 opposing that of the directly-radiated carrier wave, thus reradiating or reflecting the directly-radiated carrier wave. It is only necessary to 15 add that the operation of the key 32 effectively modifies the response of the antenna 29, 30 to the received carrier wave, whereby the reradiated carrier wave is modulated with a desired signal to be transmitted. In this regard, the transmission line 31 acts as an impedance having a value at 20 its input end substantially equal to that at its remote end, thus having large impedance across its input terminals when the key 32 is open and substantially zero impedance when the key 32 is closed. In considering the operation of the receiver 33 of this modification, and referring to 25 the curves of Fig. 5, the receiver 33 is coupled through the transmission line 34 to a potential antinode on the transmission line 31, whereby a received carrier wave is applied to the input circuit of the oscillator-modulator 36. The oscillator-modulator 36 converts the received carrier wave to an intermediate-frequency carrier wave which is amplified by the amplifier 37 and applied to the frequency detector 38. Since the received carrier wave is frequency modulated, as 30 represented by the curve A' of Fig. 5, and since the detector input transformer 41 is tuned to the nominal frequency of the carrier wave applied thereto, an audio-frequency signal is derived across the rectifier load impedance 43 having an 35 amplitude characteristic as represented by curve E. This signal effectively constitutes a keying tone which appears when the key 18, Fig. 1, is closed, as during the interval t_5 , and is absent when the key is open, as during the interval t_6 , 40 whereby the desired signal is transmitted in code form as dots and dashes in conventional manner. The audio-frequency signal derived across the rectifier load impedance 43 is amplified by the 45 audio-frequency amplifier 39 and is reproduced 50 by the signal-reproducing device 40.

It may be noted that when the modified form of the invention of Fig. 4 is used with a transmitting station of the type shown in Fig. 1, a two-way carrier-wave communication system is provided and the two-way operation is conventional in that the station which wishes to receive closes its key while the other transmits. Each station can "break in" as a side-tone signal is heard by the operator who is transmitting and this is interrupted when the key of the other station is opened.

65 It will be evident from the foregoing description of the invention that the carrier-wave communication system thereof comprises a transmitting station 10 which includes means for generating and directly radiating a modulated carrier wave having both amplitude-modulation and frequency-modulation components. One type of the modulation components comprises a signal to be transmitted to a remote point. There is also provided in the system means, including a dipole antenna 29, 30, situated at the remote point and adapted to respond to the carrier wave and to 70 reradiate carrier-wave energy directly radiated thereto from the station 10. Means, comprising 75

the carrier-wave receiver 33, is included in the last-mentioned means and is responsive to the aforementioned one type of modulation components for deriving and utilizing the transmitted signal. The means situated at the remote point 5 also includes means comprising the key 32 for modulating the reradiated carrier wave with a second signal to be transmitted. Receiving means in the system, this means comprising a radio receiver 22, receives the reradiated carrier wave and is dependent upon the other type of the modulation components of the radiated carrier wave for deriving from the received carrier wave the second signal. The derived signal last mentioned is applied to the head phones 28 for utilization.

Fig. 6 represents an additional form of carrier-wave radiating means essentially the same as that of Fig. 4, similar circuit elements being designated by similar reference characters, except that the transmission line 31' in this instance has a length equal to one-fourth or odd multiples of one-fourth of the nominal wave length of the received carrier wave and the key 32 is arranged to open-circuit the remote end of the transmission line 31' to condition the antenna 29, 30 to reradiate the carrier wave received thereby. Here the transmission line 31', as before, has a value of impedance across its input terminals which depends upon whether the key 32 is open or closed. In this modification, however, the input terminal impedance is very large when the key 32 is closed and substantially zero when the key 32 is open. The operation of this modified form of carrier-wave radiating means is otherwise essentially similar to that of Fig. 4 and will not be repeated.

While the invention has been described as embodied in a radio carrier-wave system, it will be evident that the invention is equally suited for use in a system employing supersonic sound waves.

From the above description of the invention it will be evident that a carrier-wave communication system embodying the invention has the advantage that a relatively light weight, inexpensive, rugged and highly reliable transmitter unit is provided. This unit contains no vacuum-tube apparatus and thus is not subject to failures due thereto, nor does it possess any moving parts except a circuit interrupter by which the reradiated carrier wave is modulated with the desired signal to be transmitted, nor does it require any source of battery power of any type for energization. The antenna of the transmitter unit thus provided may be made quite small where carrier waves of high frequency are used for communication, thus enabling the transmitter unit to be easily transported by a single person. These advantages are of great importance in many applications, as, for example, in military operations.

While there have been described what are at present considered to be the preferred embodiments of this invention, it will be obvious to those skilled in the art that various changes and modifications may be made therein without departing from the invention, and it is, therefore, aimed in the appended claims to cover all such changes and modifications as fall within the true spirit and scope of the invention.

What is claimed is:

1. A carrier-wave communication system comprising, a transmitting station including means for generating and directly radiating a modulated carrier wave, carrier-wave radiating means

remotely situated from said station and adapted to be solely energized by said carrier wave and thereby to reradiate carrier-wave energy directly radiated thereto from said station, means for modulating said reradiated carrier wave with a desired signal to be transmitted, means for receiving said reradiated carrier wave and dependent upon the modulation of said radiated carrier wave for deriving from said received carrier wave the desired modulation-signal components thereof, and means coupled to said last-mentioned means for utilizing said desired modulation-signal components.

2. A carrier-wave communication system comprising, a transmitting station including means for generating and directly radiating a frequency-modulated carrier wave, carrier-wave radiating means remotely situated from said station and adapted to respond to said carrier wave and to reradiate carrier-wave energy directly radiated thereto from said station, means coupled to said carrier-wave reradiating means for modulating said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

3. A carrier-wave communication system comprising, a transmitting station including means for generating and directly radiating a carrier wave frequency-modulated with a periodic modulating signal, carrier-wave radiating means remotely situated from said station and adapted to respond to said carrier wave and to reradiate carrier-wave energy directly radiated thereto from said station, means for modulating said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

4. A carrier-wave communication system comprising, a transmitting station including means for generating and directly radiating a carrier wave frequency-modulated with a periodic modulating signal of approximately saw-tooth wave form, carrier-wave radiating means remotely situated from said station and adapted to respond to said carrier wave and to reradiate carrier-wave energy directly radiated thereto from said station, means for modulating said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

5. A carrier-wave communication system comprising, a transmitting station including means for generating and directly radiating a carrier wave frequency-modulated with a periodic modulating signal of approximately linear saw-tooth wave form, carrier-wave radiating means remotely situated from said station and adapted to respond to said carrier wave and to reradiate car-

rier-wave energy directly radiated thereto from said station, means for modifying the response of said carrier-wave reradiating means to said directly-radiated carrier wave to modulate said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

6. A carrier-wave communication system comprising, a transmitting station including means for generating and directly radiating a carrier wave frequency-modulated with a modulation signal of approximately symmetrical saw-tooth wave form, antenna means remotely situated from said station and adapted to respond to said carrier wave and to reradiate carrier-wave energy directly radiated thereto from said station, means for modulating said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

7. A carrier-wave communication system comprising, a transmitting station including means for generating and directly radiating a frequency-modulated carrier wave, antenna means remotely situated from said station and tuned to the nominal frequency of said carrier wave to reradiate carrier-wave energy directly radiated thereto from said station, means for modulating said reradiated carrier wave with a desired signal to be transmitted, means for receiving said reradiated carrier wave and dependent upon the frequency modulation of said radiated carrier wave for deriving from said received carrier wave the desired modulation-signal components thereof, and means coupled to said last-mentioned means for utilizing said desired modulation-signal components.

8. A carrier-wave communication system comprising, a transmitting station including means for generating and directly radiating a modulated carrier wave, an antenna remotely situated from said station, means for tuning said antenna to be responsive to said carrier wave and to reradiate carrier-wave energy directly radiated thereto from said station, means for modifying the tuning of said antenna to modulate said reradiated carrier wave with a desired signal to be transmitted, means for receiving said reradiated carrier wave and dependent upon the modulation of said radiated carrier wave for deriving from said received carrier wave the desired modulation-signal components thereof, and means coupled to said last-mentioned means for utilizing said desired modulation-signal components.

9. A carrier-wave communication system comprising, a transmitting station including means for generating and directly radiating a modulated carrier wave, antenna means remotely situated from said station and adapted to respond to said carrier wave and to reradiate carrier-wave energy directly radiated thereto from said station, circuit-interrupting means included in circuit with said antenna means for modulating said reradiated carrier wave with a desired signal to be transmitted, means for receiving said reradiated

carrier wave and dependent upon the modulation of said radiated carrier wave for deriving from said received carrier wave the desired modulation-signal components thereof, and means coupled to said last-mentioned means for utilizing said desired modulation-signal components.

10. A carrier-wave communication system comprising, a transmitting station including means for generating and directly radiating a modulated carrier wave, a loop antenna remotely situated from said station and adapted to respond to said carrier wave and to reradiate carrier-wave energy directly radiated thereto from said station, circuit-interrupting means included in circuit with

15 a winding of said loop antenna for modulating said reradiated carrier wave with a desired signal to be transmitted, means for receiving said reradiated carrier wave and dependent upon the modulation of said radiated carrier wave for deriving from said received carrier wave the desired modulation-signal components thereof, and means coupled to said last-mentioned means for utilizing said desired modulation-signal components.

20 11. A carrier-wave communication system comprising, a transmitting station including means for generating and directly radiating a carrier wave, an antenna system remotely situated from said station, resonant means coupled to said antenna system to adapt said system to respond to said carrier wave and to reradiate carrier-wave energy directly radiated thereto from said station, means for modifying the resonant characteristic of said resonant means to modulate said reradiated carrier wave with a desired signal to be transmitted, means for receiving said reradiated carrier wave and for deriving therefrom the desired modulation-signal components thereof, and means coupled to said last-mentioned means for utilizing said desired modulation-signal components.

25 12. A carrier-wave communication system comprising, a transmitting station including means for generating and directly radiating a carrier wave, a dipole antenna, a resonant transmission line coupled to said antenna to adapt said antenna to be responsive to said carrier wave and to reradiate carrier-wave energy directly radiated thereto from said station, means coupled to said transmission line for modulating said reradiated carrier wave with a desired signal to be transmitted, means for receiving said reradiated carrier wave and for deriving therefrom the desired modulation-signal components thereof, and means coupled to said last-mentioned means for utilizing said desired modulation-signal components.

30 13. A carrier-wave communication system comprising, a transmitting station including means for generating and directly radiating a carrier wave, a dipole antenna, a resonant transmission line coupled to said antenna to adapt said antenna to be responsive to said carrier wave and to reradiate carrier-wave energy directly radiated thereto from said station, circuit-interrupting means coupled to said transmission line selectively to short-circuit and open-circuit the remote end thereof to modulate said reradiated carrier wave with a desired signal to be transmitted, means for receiving said reradiated carrier wave and for deriving therefrom the desired modulation-signal components thereof, and means coupled to said last-mentioned means for utilizing said desired modulation-signal components.

35 14. A carrier-wave communication system

comprising, a transmitting station including means for generating and directly radiating a carrier wave, a dipole antenna, a resonant transmission line coupled to said antenna and having an effective length equal to multiples of one-half the nominal wave length of said carrier wave to adapt said antenna to be responsive to said carrier wave and to reradiate carrier-wave energy directly radiated thereto from said station, circuit-interrupting means coupled to said transmission line at the end thereof remote from said antenna selectively to short-circuit and open-circuit the said remote end to cause said antenna respectively to reradiate and not to reradiate said directly-radiated carrier-wave energy, thereby to modulate said reradiated carrier wave with a desired signal to be transmitted, means for receiving said reradiated carrier wave and for deriving therefrom the desired modulation-signal components thereof, and means coupled to said last-mentioned means for utilizing said desired modulation-signal components.

15. A carrier-wave communication system comprising, a transmitting station including means for generating and directly radiating a carrier wave, a dipole antenna, a resonant transmission line coupled to said antenna and having an effective length equal to odd multiples of one-quarter the nominal wave length of said carrier wave to adapt said antenna to be responsive to said carrier wave and to reradiate carrier-wave energy directly radiated thereby from said station, circuit-interrupting means coupled to said transmission line at the end thereof remote from said antenna selectively to open-circuit and short-circuit the said remote end to cause said antenna respectively to reradiate and not to reradiate said directly-radiated carrier-wave energy, thereby to modulate said reradiated carrier wave with a desired signal to be transmitted, means for receiving said reradiated carrier wave and for deriving therefrom the desired modulation signal components thereof, and means coupled to said last-mentioned means for utilizing said desired modulation-signal components.

16. A carrier-wave communication system comprising, a transmitting station including means for generating and directly radiating a modulated carrier wave, carrier-wave radiating means remotely situated from said station and adapted to be solely energized by said carrier wave and thereby to reradiate carrier-wave energy directly radiated thereto from said station, means for modulating said reradiated carrier wave with a desired signal to be transmitted, means responsive both to said directly-radiated and reradiated carrier waves and dependent upon the modulation of said radiated carrier wave for deriving the desired modulation-signal components of said reradiated carrier wave, and means coupled to said last-mentioned means for utilizing said desired modulation-signal components.

17. A carrier-wave communication system comprising, a transmitting station including means for generating and directly radiating a carrier wave frequency-modulated with a periodic modulating signal of approximately saw-tooth wave form, carrier-wave radiating means remotely situated from said station and adapted to respond to said carrier wave and to reradiate carrier-wave energy directly radiated thereto from said station, means for modulating said reradia-

ated carrier wave with a desired signal to be transmitted, means for receiving said directly-radiated carrier wave and said reradiated carrier wave and for combining said carrier waves to derive a signal of audible frequency modulated with said desired signal, and means coupled to said last-mentioned means for utilizing said signal of audible frequency.

18. A carrier-wave communication system comprising, a transmitting station including means for generating and directly radiating a carrier wave modulated by a first modulation signal, means for additionally modulating said carrier wave with a second signal to be transmitted to a remote point, carrier-wave radiating means situated at said remote point and adapted to be solely energized by said carrier wave and thereby to reradiate carrier-wave energy directly radiated thereto from said station, means coupled to said carrier-wave radiating means for deriving from said directly-radiated carrier wave the modulation-signal components thereof corresponding to said second signal and for utilizing said derived modulation-signal components, means for modulating said reradiating carrier wave with a desired signal to be transmitted to a point remote from said carrier-wave radiating means, means situated at said last-named remote point for receiving said reradiated carrier wave and dependent upon that modulation of said directly radiated carrier wave which corresponds to said first modulation signal for deriving from said received reradiated carrier wave the desired modulation-signal components thereof, and means coupled to said last-named means for utilizing said last-named signal-modulation components.

19. A carrier-wave communication system comprising, a transmitting station including means for generating and directly radiating a modulated carrier wave having both amplitude-modulation and frequency-modulation components, one type of said modulation components comprising a signal to be transmitted to a remote point, means situated at said remote point and adapted to respond to said carrier wave and to reradiate carrier-wave energy directly radiated thereto from said station, means included in said last-mentioned means and responsive to said one type of modulation components for deriving and utilizing said signal to be transmitted, said means situated at said remote point also including means for modulating said reradiated carrier wave with a second signal to be transmitted, means for receiving said reradiated carrier wave and dependent upon the other type of said modulation components of said radiated carrier wave for deriving from said received carrier wave said second signal, and means coupled to said last-mentioned means for utilizing said second signal.
